UNITED STATES PATENT OFFICE

106,221

DESIGN FOR AN ELECTRICALLY OPERATED SOUND SIGNAL

John Gordon Sparkes, Great Neck, N. Y., assignor
to Nutone Chimes Incorporated, New York,
N. Y., a corporation of New York

Application March 29, 1937, Serial No. 68,458

Term of patent 3½ years

To all whom it may concern:

Be it known that I, John Gordon Sparkes, a citizen of the United States, residing at 6 Baker Hill Road, Great Neck, Long Island, in the county of Nassau and State of New York, have invented a new, original, and ornamental Design for an Electrically Operated Sound Signal, of which the following is a specification, reference being had to the accompanying drawing, forming a part thereof.

The figure is a perspective view of an electrically operated sound signal, showing my new design.

I claim:

The ornamental design for an electrically operated sound signal as shown.

JOHN GORDON SPARKES.
